UNITED STATES PATENT OFFICE.

CHARLES G. RICHARDSON, OF SPRINGFIELD, VERMONT, ASSIGNOR TO PARKS & WOOLSON MACHINE COMPANY, OF SPRINGFIELD, VERMONT, A CORPORATION OF VERMONT.

YARD-NUMBERING MACHINE.

Application filed March 2, 1923. Serial No. 622,419.

This invention relates to machines for yard numbering and if desired trade-marking fabrics, and is intended to provide a reliable and efficient mechanism by which a 5 piece of cloth whether cotton, woolen, silk or other fiber may be accurately and quickly marked at any desired intervals according to its actual measured length with yard-indicating numerals so that the length to any 10 marked point in the cloth will be accurately and clearly indicated.

Heretofore the automatic yard-marking of cloth has been effected through the use of inked dies but the use of such ink is objectionable in many cases and does not yield satisfactory results on certain kinds of fabric especially such fabrics as woolens or the like.

The present invention affords a rapid 20 means of yard numbering all sorts of fabrics in a most satisfactory and accurate manner by the use of a continuous strip of tape to which yard-marking stamps, and if desired, other transfer stamps have been applied, 25 and permits a very close and compact arrangement of the stamps on the tape so that a strip or tape of transfer stamps, say approximately five feet in length, may serve to mark each consecutive yard of a 60 yard 30 piece with the appropriate yard numerals to indicate the length from any marked point to the initial end of a piece of cloth. Moreover, sufficient time is given for pressing each stamp to the cloth in order to effect a 35 perfect transfer while the cloth is being rapidly fed through the machine, thus securing most clearly defined and accurate markings while no time is lost in drying the stamps impressed on the cloth.

To this end, broadly speaking, the invention 40 comprises a cloth-measuring drum with which is cooperatively combined means for feeding in consecutive order a progressive series of yard-indicating numerals composed 45 of transfer stamps and means for transferring said stamps to the appropriate portions of the cloth to indicate on the cloth its correct yard measurements to each stamped point from the initial end of the cloth. The 50 invention further comprises other features of construction and arrangement by which the different functions of the mechanism, such as feeding the stamp tape, its replenishment, the transfer of the stamp to the

appropriate portion of the cloth and the determination of measurement between the stamps applied may be effected as well as the provision of appropriate adjustment by which the operations of the machine may be varied to suit different requirements, all of 55 which will be described in detail in this specification and will be defined in the claims hereto annexed.

In the accompanying drawings is illustrated a convenient and practical form of 60 machine embodying the principles of this invention, in which:

Figure 1 is a plan view of a measuring drum equipped with a yard numbering mechanism.

Figure 1^a is a detail view showing the means for locking the cloth drum section, the revolving head and the fixed head together.

Figure 2 is a diagrammatic view in side 70 elevation illustrating the travel of the yard numbering tape.

Figure 3 is a central vertical section showing the operative mechanisms for feeding the numbering tape and transferring the 75 yard numbers to the fabric at proper distances.

Figure 4 is a detail view of the transfer actuating arm.

Figure 5 is a horizontal longitudinal section of the tape winding reel.

Figure 6 is an intermediate cross sectional view thereof.

Figure 7 is a cross section through the measuring drum and through the tape winding reel showing the stamp transfer or 90 pressing mechanism.

Figure 8 is a central cross sectional view of the tape supply reel.

Figure 9 is a diagrammatic view illustrating the travel of the cloth around the measuring drum.

Figure 10 is a cross sectional view illustrating the gearing train for driving the tape feeding mechanism.

Figure 11 is a cross sectional view of the intermittent actuating mechanism by which the transfer mechanism is moved or actuated.

Figure 12 is a plan view illustrating a 105 yard numbering tape such as is used in the machine.

In the present instance I have illustrated

the invention as applied to a well known type of yard measuring drum which, in this case, comprises a cylindrical shell of say one yard in circumference having a frictional 5 surface for engaging the cloth which passes over and around the greater part of its circumference as illustrated diagrammatically in Figure 9.

The cylindrical shell of the cylinder at 10 that portion embracing the principal part of the operating mechanism is shown made in two arcuate sections 1 and 2 with a window or opening at 2^a to allow the interior platen or pressure to move upward to hotpress the 15 interposed tape against the under face of the traveling cloth or fabric. The shell is continued toward the right by a cylindrical section 1^a of any desired or convenient width, the object of sectioning the left hand end 20 closing the working mechanism being to afford access to the interior working parts.

The sections 1 and 2 are supported on two main heads or spiders 3 and 4 which are connected by a main tubular truss 5 which also 25 affords a support for various parts of the mechanism while forming the backbone of the shell-supporting frame work. On this tubular truss or backbone 5 are also mounted any convenient number of interior shell-supporting spiders, as shown at 8 and 9 in Figure 3.

It will be understood that all the interior working parts revolve with the drum and are actuated to function at predetermined points in the revolution of the drum, as supplemental tie rods 6 serve to reenforce and tie together the heads or spiders of the frame work above described. The revolving head 3 is mounted on a rotatable hollow 40 shaft 30 carried in suitable bearings in the hub 31 of a fixed or stationary head 32, and said shaft 30 is provided with a pair of commutator rings 33 with which are connected the respective conductors 33^a which are led 45 to binding posts 33^b on the heated bed 54 of the tape presser or platen of the transfer mechanism to be presently described.

The yard numbering tape or strip 100 is usually made of thin tissue paper on which 50 are placed, at close intervals, the yard numbering marks in the form of transfer stamps, commonly known as decalcomania stamps, which impress the yard numbers successively upon the cloth at regular intervals of one yard or of fractions or multiples of a yard, according to the specific setting up of the machine. In the present case the cloth cylinder 1 is assumed to be a yard in circumference, and the cloth is yard numbered at each consecutive yard so that when 55 the initial end of the cloth is wound on to the bolt the highest yardage number is in the outside fold or turn of the cloth and as different lengths are cut off an inspection of 60 the outside yard number will always show

correctly the individual number of yards remaining in the piece.

Having particular reference first to Figures 1, 2 and 10 I will now describe the mechanism for intermittently feeding the 70 yard numbering tape so that at each revolution of the drum the next consecutive yard numbering stamp is brought into proper position for transfer to the cloth. Generally speaking this mechanism comprises a sprocket driven reel 14 which winds the forward end of the tape on itself by an intermittent movement of a predetermined distance which draws or unwinds the coiled tape 75 from the supply wheel 60.

The mechanism shown is driven by means of the actuating tooth wheel or pinion 21 carried on a rotary shaft 22^a which revolves with the drum, the teeth of said pinion engaging spiral ribs 34 on the interior face of the 80 fixed head 32 the direction of the spirals being indicated in dotted lines in Figure 10 as viewed from the interior of the drum. The spirally curved ribs 34 are so designed that each cooperating pair of ribs, as they travel 85 across the plane of revolution of the pinion 21, rotate the pinion in a contraclock-wise direction as viewed in Figure 3. This intermittent rotative movement of the pinion is transmitted to the winding reel 14 through a train of change gearing and a 90 sprocket chain, as will now be described.

As best shown in Figures 1 and 10 the actuating pinion 21, mounted on the shaft 22^a, causes said shaft to rotate by means of a 95 sliding ratchet sleeve 22 which is normally spring-pressed by means of the helical spring 23 into operative engagement with the ratchet teeth along the hub of the pinion 21. The object of this ratchet connection to the shaft 22^a is to permit, temporarily, the breaking of the operative connection between the drive pinion and the shaft in order to turn the tape-feeding train of 100 gearing and sprocket chain to adjust the tape to any desired position or, when putting in a new tape, without having to 105 re- 110 115 120 125 130 135 140 145 150 155 160 165 170 175 180 is secured a U-shaped bracket or yoke 22^d which carries a guide roll or the idler 22^e for supporting and guiding the traveling tape after it leaves the platen and also affording a support for the pivotal presser plate which cooperates with the heated presser or platen in the stamp-transferring operation, as will be presently described.

A similar guide roll 29^f is compounded with the sprocket 29^a and cooperates with a gripping roll 29^c mounted in the pivotal arm 16 to which is secured a tension spring 16^a to press the roll 29^c into firm contact against the roll 29^b so as to form a pair of strong rolls similar to wringer rolls for the purpose of drawing predetermined lengths of the tape at each feeding motion off from the supply wheel 60 and past the platen 54, as diagrammatically illustrated in Figure 2.

The winding reel 14 is intended to take up the slack of the used portion of the tape and keep it under sufficiently taut tension to prevent the tape from getting entangled in the mechanism and also, incidentally, to assist somewhat the feeding action of the feed rolls 29^c and 29^b.

This winding reel, it will be understood, handles only the used portion of the tape and is best illustrated in Figures 5, 6 and 7 and is specially constructed to facilitate the removal of a complete length of tape wound or coiled thereon. To this end the periphery of the winding reel 14 is made collapsible at one end and is provided with an axially movable stripper and is frictionally driven in order to compensate for the increasing circumference as outer coils of the tape are wound around the inner coils. A stub shaft 41, projecting from a plate 41^a, bolted to a bracket 50 which is clamped to the main stirrup 5 of the revolving frame by means of a clamping cap 50^a, serves as a stationary bearing support for the rotary reel. The reel-rotating sprocket 40 is provided with an elongated sleeve 40^a with an extension 40^b to rotate on ball bearings interposed between the sprocket hub or sleeve element and the stub shaft. The periphery or shell of the reel is formed of two semi-polygonal plates 42 which are secured to a head or disk 42^a which has frictional engagement with the rotating sprocket wheel 40 through the medium of a friction ring or washer 42^b against which the head 42^a is pressed by an adjustable spring pressure, as will now be described. The frictional head 42^a is provided with a tubular extension or sleeve 42^c projecting laterally and concentrically in the axis of rotation and carrying in its outer end a separate head 46 formed with a projecting spindle 46^a. It will be understood that the outer ring 40^b on the elongated sleeve or hub 40^a is secured thereto so as to act as if integral therewith and forms a thrust shoulder for sustaining the endwise

thrust of a helical spring 44 which is employed to press the friction head 42^a into frictional engagement with the abutting portion of the sprocket wheel 40. Instead of having the working end of said spring 44 thrust directly against the frictional head 42^a, as might be done, I prefer to provide means by which the tension or thrust of the spring against said head may be adjusted to secure satisfactory results. For this purpose I mount a thrust member 44^a loosely around the sprocket sleeve 40^a and secure it adjustably to the friction head 42^a by means of set screws 44^b. The tension of the thrust spring 44 will depend, therefore, upon the amount of its compression or expansion permitted by the spring adjusting member 44^a according to its different positions of adjustment, as the thrust on the adjustable member will be transmitted through the adjusting screws to the friction head 42^a.

The periphery of the winding reel 42 is made in sections to permit its free end to contract to facilitate drawing off the tightly wound roll of tape. Furthermore, by leaving spaces between said two peripheral plates I can employ a stripper comprising oppositely arranged hooked arms 43 which project between the adjacent edges of the two sections of the periphery and whose inner ends are secured to a sliding spool 45^a mounted on the spindle 46^a so that the movement of the spool or collar 45^a to the left also moves the stripper arms 43 in the same direction so as to start the tightly wound paper toward the collapsible end of the reel. To said spool or collar 45^a are also secured upper and lower toggle arms which form pivotal links connecting said slide collar or spool with the free or collapsible ends of the reel peripheral sections. Hence, movement of the spool to the left (Figs. 5 and 7) serves both to collapse the reel and start the withdrawal of the paper roll by means of the connected stripper arms.

The transfer of the numbering stamp to the cloth is effected by means of two opposed presser members between which the tape and edge portion of the cloth are interposed and pressed together.

The bracket 50, which is clamped to the hollow truss rod 5 of the frame, carries a transverse spindle 51 which serves both to retain the movable section 2, of the shell locked in position, and also as a support or fulcrum for the sleeve 52 of the platen arm 53 which latter, at its free end, carries the heated platen 54 in position to swing upward through the opening 2^a to press against the underside of the cloth the interposed tape. There is also provided a cooperating presser or pad 57 which sustains the outward thrust of the moving platen 54 and which revolves with the rotating drum as does the platen 54. The platen is moved up

into stamp-transferring or pressing position by means of the rock-shaft 72 whose opposite ends are supported in brackets 70, 71, clamped to the truss rod 5, said rock-shaft passing through openings in the intermediate spiders 8. On this rock-shaft 72 is secured a hub 55 carrying a laterally projecting arm terminating in a ball head 56, which is loosely held in a recess or socket in the platen arm 54 by means of a recessed or socketed retaining plate 53^a (Fig. 4). This recess is intermediate of the fulcral pin 51 of the platen. The cooperating pressing or transfer member comprises a plate 57 carried by parallel arms 57^a which are fulcrumed on pivots 57^b carried by the U-shaped bracket 22^a, previously described. An actuating link 58 forms a pivotal link connection between a projection 58^a on the platen arm 53 and the outer end of the arm or lever 57^a so that, as the platen moves outward to pressing position, the link moves the outer end of the lever 57^a outwardly thus swinging the arms 57^a upon their pivots 57^b, the parts being so proportioned that when the platen is out of operative position, that is depressed toward the center of the drum, the presser plate 57 is swung entirely clear of the cloth drum 1, so as not to overhang its periphery at all, that is, the plate 57 stands in an approximately vertical plane. The action of the two pressers in substance resembles that of a pair of shears or tongs which are normally open but which swing toward each other to grip or pinch together the interposed cloth and tape. It will be observed that as both presser elements revolve uniformly with the drum and with the travel of the cloth no time is lost in the pressing operation and the presser elements may be kept under pressure through any desired arc of revolution to effect a perfect transfer of the stamp to the cloth.

Now it will be seen that the number or frequency of the tape-feeding movements may be regulated by substituting different cam plates 32 at the head of the drum for actuating the pinion 21 since different plates may be arranged with different numbers of spiral actuating ribs or with spiral ribs arranged at different intervals around the periphery to act with greater or less frequency. It will also be seen that the distance the tape is fed on each feeding operation may be varied by changing the gear trains leading to the chain driving sprocket. However, if the number of feeding movements of the tape is varied then it will be clear that the operation of the transfer mechanism or stamp-pressing devices should be correspondingly varied and the mechanism which is provided for actuating the stamp transferring devices is constructed to allow similar flexibility in its adjustments.

As shown at the right of Figure 3, and

also in Figure 11 the rock-shaft 72 is provided with a crank arm 73 carrying a cam roller 73^a which is engaged by a cam 80 which is revolved intermittently through the agency of a sprocket chain 81, which passes partly around a central sprocket 81^a which is secured to a fixed or non-rotating spindle 81^b. The sprocket chain 81 is also passed around sprocket gears 82, 82^a and 82^b in the manner shown in Figure 11 which last-mentioned sprocket gears are carried by revolving spider 4 so that the entire sprocket chain revolves around the fixed sprocket wheel 81^a in the direction indicated by the arrows in Figure 11. The effect of this is substantially the same as if the chain were mounted on a non-revolving support and the sprocket gear 81^a rotated in the direction opposite to the revolution of the drum.

At intervals along said sprocket chain, which may be varied in order to accomplish the desired periodicity of movement, are arranged laterally projecting pins 83 which pins are arranged to engage the under flattened side of flattened disk-like arms 84 arranged on opposite sides of the sprocket wheel 82, both said disks 84 being compounded to form a single rotatable unit with the cam 80. The sprocket gear 82 is loose on the spindle 85 so that the cam 80, which actuates the rock-shaft 82, is rotated only when the projecting pins 83 engage the flat faces of the disks 84. The object of this mechanism is to give an intermittent rotation of the rock-shaft to actuate the stamp-transfer pressers at any desired periodicity to effect the stamping of the cloth at any desired intervals whether at one yard intervals, half yard or quarter yard intervals, yard and a half or two yard intervals to suit any particular requirements.

The tape-supplying reel 60 may be of any suitable construction and in this case is made to fit different widths of tape and to be rotated under a frictionally retarded drag so as to avoid paying out slack of tape as it unwinds from the reel. A bracket 61 is clamped to the main truss 5 to form a support for the solid arbor 62 which is adjustably clamped in the bracket 61 by means of the thumb screw 61^a. Loosely surrounding said arbor 62 is a screw-threaded sleeve 63 which has threaded engagement with the two disks 60^a forming the sides of the reel. By turning the disks or heads 60^a on the screw threaded sleeve 63 the heads may be brought nearer together or farther apart. A spacing sleeve 64 on which the tape is wound determines the extent of separation between the heads 60^a.

At its outer end the arbor 62 is threaded to receive an adjustable nut 62^a and a coiled spring 65 is interposed between said nut and the adjacent head 50^a of the reel, thus forming, by its frictional thrust, a

brake or retarding member tending to hold the reel against rotation while allowing it to rotate under sufficient pull from the tape as it unwinds. Adjustment of the nut varies the position and tension of the spring.

To afford access to the interior for the purpose of removing used tape and replacing new rolls of tape, the end of the shell surrounding the tape-feeding and winding mechanism is made in sections; as already explained. The smaller removable section 20, shown in Fig. 7, is provided with an inwardly projecting ear or lug 2^a, and in the transverse arm 51 there is mounted a slide bolt 2^b which, when moved toward the right, (Fig. 1) interlocks with the ear 2^a to prevent it from opening, and which when moved toward the left in Figure 1 passes through a recess 3^c in the revolving head 3 and enters or penetrates a corresponding recess formed in the stationary cam disk 32. In short, in one position of adjustment the locking bolt 2^b locks the open or pivoted section 2 in closed or operative position and this section can not be opened to gain access to the interior until the bolt 2^b has been shifted into position to lock the drum against revolution. In this way all possibility of accidental revolution of the drum, when the door tube is open, is prevented. As shown in Figure 7 the movable section 2 is pivoted at 2^x to the main frame of the drum to allow it to swing open and shut.

35. The end of the drum opposite the stamp-transferring mechanism, is supported by means of a hollow shaft 90 which passes through the center of the spider 9 and of the spider 4, and is supported in a suitable bearing bracket indicated at dotted lines at the right of Figure 1. A bracket 92 attached to said bearing carries a set screw 93 which can be set tightly against the inserted end of the stationary spindle 81^b to prevent its rotation. As shown in Figures 3 and 11 the sprocket wheels 82^b are mounted on an adjustable plate 82^c which is secured to the spider 4 by means of a bolt and slot engagement.

50. What I claim is:

1. In a yard-marking machine, the combination of a revoluble drum adapted to rotate in unison with the travel of a piece of cloth passing over its periphery in order to measure the length of the cloth, and yard-marking means comprising feeding means for feeding a progressive series of numerals composed of transfer stamps in consecutive order into proximity to the cloth, and stamp-transferring means co-ordinated with the revolving drum to transfer said stamps successively to the precise points of the cloth corresponding to the distance from the initial end thereof indicated by the stamped numeral being transferred whereby the

cloth is marked with yardage measurements at desired intervals, throughout its length, substantially as described.

2. In a yard-marking machine, the combination of a drum adapted to rotate in unison with the travel of a piece of cloth passing over its periphery in order to measure the length thereof; and yard-marking means carried by and revolving with the drum embracing a presser, means for feeding a series of transfer stamps comprising progressive yard-indicating numerals between the cloth and the presser, and means for actuating said presser to transfer the stamps successively to the cloth at predetermined intervals corresponding to the distance from the initial end of the cloth of each such marked portion, substantially as described.

3. In a yard-marking machine, the combination of a measuring drum rotatable in unison with the travel of cloth passing over its periphery, stamp-transferring means embracing opposed cooperating members revolving with the drum, actuating means operated by the revolution of the drum to operate said transferring means to transfer yard-numbering stamps at predetermined intervals on the cloth, and coacting mechanism for feeding yard numbering stamps one after another between said opposed transfer members, substantially as described.

4. In a yard-marking machine the combination of a measuring drum rotatable in unison with the travel of cloth passing over its periphery, stamp-transferring mechanism embracing a heated presser and a cooperating pressure sustaining member and actuating means therefor operated at predetermined intervals in the revolution of the drum, transfer stamp feeding means for feeding an appropriate transfer stamp to transfer position between the heated presser and the traveling cloth before each pressing movement of the hot presser in order to yard number the cloth, substantially as described.

5. In a yard-marking machine the combination of a measuring drum rotatable in unison with the travel of cloth passing over its periphery, stamp transferring mechanism embracing two cooperating pressing members and their actuating mechanism carried by and revolving with the drum, said actuating mechanism being provided with adjustments by which it can be caused to act with any desired frequency relative to a complete revolution of the drum, and means for feeding transfer stamps to the transfer mechanism said feeding means being also provided with adjustments to cause it to feed with corresponding frequency, substantially as described.

6. In a yard-numbering machine, the combination of a revoluble cloth-measuring drum, transfer stamps supplying and feed-

ing mechanism mounted inside the drum and revolving therewith, a stationary cam supported adjacent to said feeding mechanism to engage and cause actuation of said feeding mechanism at any desired frequency as the drum revolves, and stamp transfer mechanism embracing a pair of opposed pressing elements arranged to hot press an interposed stamp against an interposed portion of the cloth at any desired stage in the drum revolution in order to yard number the cloth, substantially as described.

7. In a yard-numbering machine, the combination of a revoluble drum, stamp-carrying and feeding mechanism operable to any desired points in the revolution of the drum through engagement with a cooperating controlling cam not revolving with the drum, and stamp-transferring mechanism revolving with the drum and operable to transfer the successively fed stamps to the fabric as the drum revolves in order to yard number the cloth at desired intervals, substantially as described.

8. In a yard-numbering machine, the combination with a revoluble cloth-measuring drum, means for feeding a tape-strip carrying yard numbering stamps arranged in consecutive order at any desired intervals thereon to proper transfer relation to the cloth traveling over the drum periphery, said feeding means being intermittently actuated by the revolution of the drum and having adjustment by which the frequency of the feeding movement and the distance that it feeds may be varied, and a coordinated transfer mechanism carried by and revolving with the drum to hot press each stamp on the cloth at appropriate intervals, substantially as described.

9. In a yard-numbering machine, the combination of a revoluble cloth-measuring drum comprising a peripheral shell and an interior supporting frame embracing interior heads and longitudinal connecting rods, a stamp-tape carrying reel and tape feeding mechanism secured to the supporting frame and having operative connection with an externally supported actuating member, means mounted on said interior frame for hot pressing the stamps on said tape at appropriate intervals on the cloth, said shell being provided with a removable section normally locked in operative position, substantially as described.

10. In a yard-numbering machine, the combination of a revoluble cloth measuring drum comprising a setional peripheral shell and an interior supporting frame one section of which is releasably locked in normal operative position, stamp-feeding and stamp-transferring mechanism operatively mounted on the interior frame, and locking means operable to lock the releasable section in normal closed position and to lock the drum

against rotation when the releasable section is open, substantially as described.

11. In a yard-numbering machine, the combination of a revoluble cloth measuring drum comprising a sectional peripheral shell and an interior supporting frame one section of which is releasably locked in normal operative position, stamp-feeding and stamp-transferring mechanism operatively mounted on the interior frame, and a locking bolt movable one way to release the release section and lock the drum in order to allow access to the interior and acting when moved the other way to release the drum and lock the section in closed position, substantially as described.

12. In a yard-numbering machine, the combination of a revoluble cloth-measuring drum, a rotatable reel for supporting a transfer-stamp tape, feed rolls for drawing off from said reel predetermined uniform lengths of tape, a winding reel for taking up and winding on the tape after it has passed the feed rolls, and a transfer mechanism for intermittently pressing the stamped portion of the tape against cloth, traveling over the drum periphery, the movement of said feed rolls and said reel being correlated to the rotation of said cloth measuring drum, substantially as described.

13. In a yard numbering machine, the combination with a revoluble cloth-measuring drum, means for intermittently hot pressing a consecutive series of transfer stamps on a carrier tape onto said cloth, tape feeding means embracing feed rolls adapted to draw predetermined lengths of tape across said hot presser to expose successive stamps to the transfer action of said presser, a frictionally driven winding reel for winding up the used portion of the tape, said winding reel and said feed rolls being driven from a common actuating element in coordination with said drum, substantially as described.

14. In a yard measuring and numbering machine having a revoluble measuring drum and means for transferring yard numbers from a transfer tape to the cloth at predetermined intervals, tape-feeding means embracing in combination with feed rolls, intermittently driven by the revolution of the cloth measuring drum, a revoluble tape-carrying reel arranged to deliver the tape to the feed rolls, and a frictionally driven take-up reel for keeping taut and winding on that portion of the tape from which the stamps have been transferred to the cloth, and means carried by said winding reel to strip off the tightly wound tape therefrom in order to permit attachment of another tape thereto, substantially as described.

15. In a yard numbering machine, the combination of a revoluble cloth-measuring drum, means for feeding a transfer-stamp

carrier tape into position for transfer to predetermined portions of the cloth traveling over the drum periphery, stamp-transferring devices arranged to hot press the successive stamps on the tape onto the cloth, and actuating mechanism for the stamp transfer device embracing a cam and a cam actuating element provided with a series of adjustable cam-engaging and moving members by which the cam is intermittently moved at predetermined but variable intervals, substantially as described.

16. In a yard numbering machine, the combination of a revolute cloth-measuring drum, feeding mechanism for feeding a series of yard-numbering transfer stamps in position for transfer to the cloth being measured, transfer mechanism embracing inner and outer presser members mounted to move together to hot press a stamp onto the interposed portion of the cloth traveling over the drum periphery, the outer member being movable after each pressing operation away from its position overhanging the cloth, and means dependent on the revolution of the drum to actuate said pressers, substantially as described.

17. In a yard numbering machine, the combination of a revolute cloth-measuring drum, feeding mechanism for feeding a

series of yard-numbering transfer stamps into position for transfer to the cloth being measured, transfer mechanism embracing inner and outer presser members for pressing the successive stamps onto appropriate portions of the cloth traveling thereon, and actuating mechanism for intermittently operating the inner presser in coordination with the revolution of the drum the outer member being simultaneously moved from idle to pressing position by an intermediate connection with the movable inner member, substantially as described.

18. In a yard numbering machine, the combination of a revolute cloth-measuring drum, interiorly disposed chain-driven stamp-transfer mechanism for hot pressing yard numbering transfer stamps onto predetermined portions of the cloth traveling over the drum periphery and interiorly disposed coordinated chain-driven mechanism for feeding successive yard-numbering transfer stamps to position to be acted upon by said transfer mechanisms, both chain-driven mechanisms being actuated by the revolution of the drum, substantially as described.

In witness whereof, I have subscribed the above specification.

CHARLES G. RICHARDSON.
